COMBINED EXTENSION TABLE AND CABINET

Peter H. Weber, Milwaukee, Wis., assignor to
Florence J. Sterling, Chicago, Ill.

Application May 26, 1941, Serial No. 395,211

4 Claims. (Cl. 311—2)

1

This invention relates to a combined extension table and cabinet of a type wherein the table may be readily collapsed and housed within the cabinet and as readily extended to full length beyond the cabinet.

A combined extension table and cabinet is disclosed in my prior Patent No. 2,054,843, issued September 22, 1936, in which the table top includes a series of hinged leaves foldable one upon another to permit collapse of the table into the cabinet.

An object of the present invention is to provide an extension table which may be collapsed into a cabinet without necessitating the use of hinged leaves. This I have accomplished by the provision of means for displacing one table top section out of the plane of an adjacent section to permit the latter to enter the cabinet.

Other more specific objects and advantages will appear, expressed or implied, from the following description of an illustrative embodiment of the present invention.

In the accompanying drawings:

Figure 1 is a longitudinal sectional view, along the line 1—1 of Fig. 4, of an extension table and kitchen cabinet constructed in accordance with the present invention and showing the table extended.

Fig. 2 is a similar view showing the table collapsed.

Fig. 3 is a sectional view taken substantially along the section line 3—3 of Fig. 1.

Fig. 4 is a horizontal sectional view of the cabinet showing the extended table in plan with parts broken away.

Fig. 5 is a longitudinal sectional view taken along the section line 5—5 of Fig. 4.

The extension table shown is supported at its outer end upon a pair of legs 10 rigidly attached to a rectangular frame comprising a front apron 11 and side aprons 12, the latter being connected by a horizontal plate 13. The plate 13 is braced by side pieces 14 having blocks 15 fixed between them and the side aprons 12. The frame, just described, is connected to the cabinet 16 through conventional extension slides 17, the forward end slides being rigidly attached to the side aprons 12 and the rear end slides being rigidly attached to and within the cabinet.

The table top shown is in two sections, one 50 section 18 being fixed to the frame, and the other section 19 resting upon the extension slides 17 and being separably engaged with the section 18 through conventional pin and socket connec-

2

The cabinet 16 may be of any conventional or approved design. That shown is provided with an upper compartment 21 for receiving and housing the table and a lower drawer space 22 separated therefrom by a horizontal partition 23.

In order to permit entry of the table top section 18 into the cabinet space 21, provision is made for elevating the section 19 out of the plane of the section 18 automatically as the latter approaches the cabinet. Although that might be accomplished in various ways the means shown for that purpose has proven entirely satisfactory. It includes a pair of slide plates 24 disposed within the cabinet at opposite sides of the table, each plate 24 carrying a pair of inwardly directed sheet metal fingers 25 over which the section 19 of the table top is positioned when shifted into the cabinet. The top edges of the adjacent stationary slide members 17 are preferably cut away at 26 to accommodate the fingers 25 so that the latter will not interfere with inward advance of the table top section 19 into the cabinet. Each slide plate 24 is vertically movable between appropriate guide blocks 27, and as they move upward the fingers 25, carried thereby, engage beneath the table top section 19 to lift the latter out of the plane of the other section 18 of the table top.

Provision is made for lifting both slide plates 24 automatically as the outer section 18 of the table top approaches the cabinet. This is accomplished in this instance by a pair of rocker plates 28, each being supported intermediate its ends upon a rock shaft 29 carried by partition 23, and each being so disposed that one end 30 thereof projects beneath one of the slide plates 24 while the other elevated end 31 projects beneath an actuator bar 32. The bar 32 normally rests upon the upper ends 31 of the rocker plates and extends transversely of a trip lever 33 to which it is attached intermediate the ends of the latter. The lever 33 is hingedly supported at one end 34 adjacent the rear of the cabinet and extends forwardly and upwardly therefrom, its forward end 35 being disposed within the path of travel of an actuating cam block 36 carried by and beneath the plate 13 of the table. The block 36 has an inclined edge 37 positioned to engage and depress the forward end 35 of the lever 33 as the table section 18 approaches the cabinet, to thereby actuate the rocker plates 28 and the slide plates 24 in such manner as to elevate the table top section 19 which has previously entered the cabinet.

65 It will of course be understood that, with the

3

table top section 19 thus lifted, in the manner just described, into the position shown in Fig. 2, the way is clear for entry of the table top section 18 into the cabinet beneath the section 19, as indicated also in Fig. 2. It will also be noted that during advance of the table top section 18 into the cabinet, the cam block 36 bears against the lever 33 so as to retain it in depressed position and so as to retain the table top section 19 elevated.

It will be further noted that, as the table top section 18 is withdrawn from the cabinet, the lever 33 remains in depressed position until the cam block 36 and its inclined edge 37 has cleared the forward end 35 of the lever, whereupon the table top section 19, together with its supporting slide plates 24, fall by gravity, permitting the section 19 to reassume its normal position on the extension slides 17 and permitting the lever 33 to reassume its normal elevated position.

As previously pointed out, the sections 18 and 19 of the table top are separably engaged by conventional pin and socket connections 20, when the table is extended, in order to insure accurate registration of those sections. Because of this, it is highly desirable that, in collapsing the table, these connections between the table top sections be separated before the section 19 be lifted, and that, when the table is again extended, the sections be again closely joined. Provision is therefore made for accomplishing these functions automatically.

In the device shown, automatic separation of the table top sections is effected by upright pins 38, each carried by one end of a horizontal rock plate 39, pivotally attached to the under side of the plate 13 by a screw 40 or other form of vertical pivot. A spring 40' yieldably retains each rock plate 39 in the position shown in Figs. 1 and 4, in which position the pin 38 carried thereby bears against the base of a recess 41 formed in the plate 13 and projects upwardly into open sided groove 42 formed in the lower edge of the top section 18. Each rock plate 39 also carries a depending stop member 43 which extends laterally toward the center of the table, the inner end of each being disposed to engage reduced side portions 44 of the lever end 35 as the table section 18 approaches the cabinet. Engagement of the portions 44 against the inner ends of the stop members 43 causes the plates 39 to swing in the directions of the arrows of Fig. 4, so as to cause the pins 38 to act on the adjacent edge of the table section 19 in such direction as to force the latter away from section 18 and thus separate the pin and socket connections 20. It is understood of course that this occurs before the lever end 35 is depressed by the cam block 36 and hence before the vertical slide plates 24 have been actuated to lift the table section 19.

The stops 43 ordinarily assume the vertical position shown in Figs. 1, 2 and 3, but each is hingedly mounted, as at 43', so as to swing toward the right (Figs. 1 and 2) and thereby clear the portions 44 of the lever 33 as the table section 18 is withdrawn from the cabinet.

Reengagement of the table top sections is effected automatically, whenever the table is extended, by appropriate means which will now be described. In the device shown, the means employed for that purpose includes a pair of rods 45 each having an eye 46 at its rear end, slidably engaged with a stationary horizontal bar 47 anchored in the cabinet. The forward end of each rod 45 extends loosely through a bracket 48 attached to the bottom of a block 49 which is slid-

able in a guideway 50 formed in one of the fixed blocks 15. Movement of the rod 45 within the bracket 48 is limited by a nut 45' on the rod. Each slide block 49 is connected to a similarly mounted slide block 51 through a cable 52, the cable passing around a pulley 53 stationarily mounted on the under side of the fixed block 15. Each block 51 carries a bracket 54 through which a rod 55 is loosely extended. Each rod 55 is attached to and depending from the rear edge of the table top section 19, and a nut 57 at the forward end of each rod 55 limits the movement thereof within the bracket 54.

The arrangement is such that whenever the table top section 19 is separated from section 18 in the manner above described, each rod 55 carried by section 19 acts on its slide block 51 to shift the latter with the section 19, whereupon the other slide block 49 is actuated by the cable 52 to move in the opposite direction. This of course occurs as the table top section 18 approaches the cabinet, and the two blocks 51 and 49 remain in the relative positions into which they have thus been shifted, until the table is later extended from the cabinet. As the table section 18 is withdrawn from the cabinet and the section 19 lowered onto the extension slides 17, the nuts 57 ultimately engage the brackets 54, and thereafter continued outward movement of the section 19 through the rods 55 and brackets 54, causing the section 19 to thereafter follow section 18. Both thereafter continue their outward movement until the eyes 46 of the rods 45 are arrested by the forward ends 35 of the bars 47, whereupon continued advance of table section 18 causes both slide blocks 49 to retract and both slide blocks 51 to advance with respect to the section 18, the advance of the blocks 51 being transmitted through the rods 55 and brackets 54 to advance the section 19 into close engagement with the section 18, thereby effecting re-engagement of the pin and socket connections 20.

Various changes may be made in the embodiment of the invention hereinabove specifically described without departing from or sacrificing the advantages of the invention as defined in the appended claims.

I claim:

1. A collapsible table for the purpose described having a lengthwise extensible and collapsible frame, a table top comprising a plurality of separable sections in coplanar relation when said frame is extended, one of said sections being movable with the movable end of said frame, a support for said movable frame end movable therewith, means at the other end of said frame for elevating another of said sections clear of the plane of said first named sections to admit the latter beneath said elevated section when said frame is collapsed, and means responsive to collapse of said frame for actuating said elevating means.

2. A collapsible table for the purpose described having a lengthwise extensible and collapsible frame, a table top comprising a plurality of separable sections in coplanar relation when said frame is extended, means for separating said sections, one of said sections being movable with the movable end of said frame, means at the opposite end of said frame for elevating another of said sections clear of the plane of said first named section to admit the latter beneath said elevated section when said frame is collapsed, and means responsive to collapse of said frame for actuating

said section separating means and said elevating means.

3. A collapsible table for the purpose described having a lengthwise extensible and collapsible frame, a table top comprising a plurality of separable sections in coplanar relation when said frame is extended, means for separating said sections, one of said sections being movable with the movable end of said frame, means at the opposite end of said frame for elevating another of said sections clear of the plane of said first named section to admit the latter beneath said elevated section when said frame is collapsed, means responsive to collapse of said frame for actuating said section separating means and said elevating means, and means responsive to extension of said frame for positioning said sections in edge-to-edge relation.

4. A collapsible table for the purpose described having a lengthwise extensible and collapsible frame, a table top comprising a plurality of separable sections in coplanar edge-to-edge relation when said frame is extended, means responsive to collapse of said frame for separating said sections, means responsive to collapse of said frame for elevating one of said sections above the plane of another of said sections so as to admit the latter beneath said elevated section, said last named means being effective to return said elevated section to the plane of said other section upon extension of said frame, and means responsive to extension of said frame for returning said sections into edge-to-edge relation.

PETER H. WEBER.
